(57) **CLAIM**

The ornamental design for american civilian aviation pilot wings, as shown and described.

DESCRIPTION

FIG. 1 is a perspective view of one side and the front of the american civilian aviation pilot wings of my new design; FIG. 2 is a front elevation view thereof; FIG. 3 is a top plan view thereof; FIG. 4 is a bottom plan view thereof; FIG. 5 is a left side elevation view thereof; and, FIG. 6 is a right side elevation view thereof. The rear view is plain and unornamented and forms no part of the claimed design.
